United States Patent

Des. 235,613
Patented July 1, 1975

235,613

SCREW STARTER

John Donald Olson, Kensington, and Wojciech Stanislaw Gutowski, Southington, Conn., assignors to The Stanley Works, New Britain, Conn.

Original design application Feb. 14, 1972, Ser. No. 226,381, now Patent No. 233,132, dated Oct. 8, 1974. Divided and this application July 9, 1973, Ser. No. 377,803

Term of patent 14 years

Int. Cl. D8—05

U.S. Cl. D8—86

FIG. 1 is a perspective view of a screw starter showing our new design;

FIG. 2 is a plan view thereof;

FIG. 3 is a bottom view thereof;

FIG. 4 is a side elevational view thereof to a somewhat reduced scale with a slide portion extended;

FIG. 5 is an elevational view of the handle end of the screw starter;

FIG. 6 is an elevational view of the jaw end of the screw starter.

The present application is a division of our copending application Ser. No. 226,381, filed Feb. 14, 1972, now Pat. No. D. 233,132 issued Oct. 8, 1974.

We claim:

The ornamental design for a screw starter, as shown and described.
